UNITED STATES PATENT OFFICE.

GUSTAV BENISCH, OF BROOKLYN, NEW YORK.

PIVOTED DOOR.

1,147,361.

Specification of Letters Patent. Patented July 20, 1915.

Application filed February 15, 1915. Serial No. 8,395.

To all whom it may concern:

Be it known that I, GUSTAV BENISCH, a citizen of the United States of America, and resident of the borough of Brooklyn, in the county of Kings and State of New York, have invented certain new and useful Improvements in Pivoted Doors, of which the following is a specification.

This invention relates to improvements in pivoted doors for mausoleums constructed of granite or the like, and other such permanent structures exposed to the elements. These doors as heretofore constructed were usually set on a bronze saddle and swung inwardly, so that there existed an exposed joint between the door and saddle, which would allow rain to beat or seep into the structure, and thereby gradually deteriorate the same, and endanger its permanence. As mausoleums to be durable must be constructed entirely of everlasting material, such expedients as rubber or felt weather strips will not help matters, as they are not everlasting, and furthermore, detract from the dignity and beauty of such a structure.

The object of the present invention is to overcome these objections, by providing a door to swing outwardly and permanent means abutting said door for preventing entrance of rain into the structure.

A further object is to provide an adjustable pivot for the door, so as to provide for any inaccuracy in the drilling of pivot holes in the granite or other material used before the same is set up, and thereby establish close joints between the door and frame.

With these and other objects in view, my invention consists of the novel features, construction and arrangement of parts, hereinafter more fully described and pointed out in the claims.

In the accompanying drawings, Figure 1 is a front elevational view of my improved door; Fig. 2 is a vertical section of the same; Fig. 3 is a horizontal section thereof; Fig. 4 is a sectional detail showing a form of bronze saddle for the door; Fig. 5 is a modified form of the same; Fig. 6 is an enlarged vertical section of the adjustable pivot; Fig. 7 is a horizontal section of the same on the line 7-7 of Fig. 6; Fig. 8 is a plan of a modified form of adjustable pivot; and Fig. 9 is a sectional view of a modified form of door and jamb.

Similar reference characters indicate corresponding parts throughout the several views.

Referring to the drawings, and more particularly to Fig. 1 thereof, outwardly swinging doors 1 and 2 are set in a frame comprising jambs 3 and 4, a lintel 5, and a platform 6 constructed of granite, concrete or the like. The said jambs are set out in front of the door at 7 and 8, and the lintel and platform are set out behind the same at 9 and 10 to form permanent abutments for the said door, and the outer ends of the said door are rounded at 11 and 12 to permit swinging of the same on the pivots herein-after described. If desired, the doors need be rounded only at the vertical edges adjacent the jambs, but this is not necessary, as they may be of any suitable shape.

In the form shown in Fig. 4, a bronze saddle 13 lies underneath the door and abuts against the set-out portion of the platform, and in the form shown in Fig. 5, a bronze saddle 14 having a set-out portion 15 is employed, which also abuts against the set-out portion of the platform. In the first form the swinging door abuts against the set-out portion 9 of the platform, while in the latter, the door abuts against the bronze set-out portion 15 of the saddle. Holes 16 are drilled in the platform and lintel at either side thereof, having their center approximately in the axis of the rounded ends 11 and 12 of the door, and bronze rings 17 provided on their inner surface with teeth are secured by babbitt or other suitable means into the said holes before the granite or concrete is set. After the same is set, the eccentric rings 18 of bronze provided on their inner and outer surfaces with teeth and eccentric rings 19 of bronze having teeth on their outer surface are interlocked with the said rings 17 to receive pivots. As will be seen, the pivot hole thus formed may be varied in any direction by changing the positions of the various rings with respect to each other. When the rings are properly arranged, the doors are set thereon, and bolts or pivots 20, provided in recesses 21 in the doors are slid into the same and secured in place by screws 22.

In the form shown in Fig. 8, disks 23 having apertures 24 are secured into the lintel and platform in the manner above described.

The said apertures may be square (as shown), rectangular, polygonal, or other suitable shape, into which a plate 25 of corresponding shape is adapted to be fitted. 5 When the structure is set up, the exact pivot points are ascertained on the plates 24 and holes 26 drilled therein accordingly, for receiving the bolts or pivots 20 of the door.

In Fig. 9 a modified form of door and 10 joint is shown, in which the pivoted end of the door is engaged or checked by a set-out portion 29 of the jamb at its front edge, and at its rear edge by a set-out portion 30 thereof. The intermediate portions 27 and 15 28 of the door and 31 and 32 of the jamb are so shaped that in swinging, all points of the door will clear the jamb. In this form, the top and bottom of the door are also abutted at the rear by a set-out portion of the 20 platform and lintel, as in the first described form.

It is obvious that in this way an exact fitting of the door is obtained, so that there can be no loose joints, to permit the leaking 25 in of water or the like.

I have illustrated preferred and satisfactory forms of my invention, but it is obvious that changes may be made therein and that other materials than bronzes and granites 30 may be used as well, without departing from the spirit and scope thereof, as defined in the appended claims.

I claim:

1. In a pivoted door adapted to swing 35 outwardly, a set-out check on the sill, and a set-out check on the lintel, said checks being adapted to engage the upper and lower rear edges of the door in closed position, a door-frame provided with a set-out check on 40 the jamb adapted to engage the front edges of the door in closed position, the pivotal point of the said door being at the upper and lower ends of the said door and at a point removed from the side of the said door 45 the front edges of the door adapted to engage the said set-out checks of the jamb in closed position, and to swing free of the said checks in open position, and the rear edges of the said door being adapted to clear the

said checks of the lintel and sill in open 50 position.

2. In a pivoted door adapted to swing outwardly, a door-frame provided with a set-out check on the jamb, adapted to engage the front edges of the door in closed 55 position, a second set-out check on the jamb adapted to engage the rear edges of the door, a set-out check on the sill, a set-out check on the lintel adapted to engage the upper and lower rear edges of the door in 60 closed position, the pivotal point of the said door being at the upper and lower ends of the said door at a point removed from the side of the said door, the front edges of the door adapted to engage the said first-mentioned set-out check of the jamb in closed 65 position and to swing free of the said check in open position, and the rear edges of the door being adapted to clear the said last-mentioned check of the jamb and the checks 70 of the lintel and sill in open position.

3. In a pivoted door adapted to swing outwardly, and having its ends shaped to snugly fit the door-frame in closed position, a door-frame provided with a set-out check 75 on the jamb adapted to engage the front edges of the door in closed position, a set-out check on the sill, and a set-out check on the lintel adapted to engage the upper and lower rear edges of the door in closed 80 position, the pivotal point of the said door being at the upper and lower ends of the said door and at a point removed from the side of the said door, the front edges of the door adapted to engage the said set-out checks 85 of the jamb in closed position, and to swing free of the said checks in open position, and the rear edges of the said door being adapted to clear the said checks of the lintel and sill in open position. 90

In testimony that I claim the foregoing as my invention, I have signed my name in presence of two subscribing witnesses.

GUSTAV BENISCH.
